(57) **CLAIM**

We claim the ornamental design for a dental paste cup holder, as shown and described.

DESCRIPTION

FIG. 1 is a perspective view of a dental paste cup holder according to the new design;

FIG. 2 is a front view of the dental paste cup holder shown in FIG. 1;

FIG. 3 is a back view of the dental paste cup holder shown in FIG. 1;

FIG. 4 is a first side view of the dental paste cup holder shown in FIG. 1;

FIG. 5 is a second side view of the dental paste cup holder shown in FIG. 1;

FIG. 6 is a top view of the dental paste cup holder shown in FIG. 1; and,

FIG. 7 is a bottom view of the dental paste cup holder shown in FIG. 1.

The broken lines are included for the purpose of illustrating portions of the dental paste cup holder that forms no part of the claimed design.
